UNITED STATES PATENT OFFICE.

JOHN A. SECOR, OF NEW YORK, N. Y.

SPEED-REGULATOR FOR EXPLOSIVE-ENGINES.

SPECIFICATION forming part of Letters Patent No. 623,567, dated April 25, 1899.

Application filed October 7, 1897. Serial No. 654,849. (No model.)

To all whom it may concern:

Be it known that I, JOHN A. SECOR, a citizen of the United States, residing in the city of New York, (Brooklyn,) in the county of 5 Kings and State of New York, have invented certain new and useful Improvements in Explosive-Engines, of which the following is a specification, reference being had to the accompanying drawings, forming a part thereof.

10 This invention relates to engines of that class in which the propulsive force is derived from the explosion of a hydrocarbon gas or gaseous mixture in rear of the piston, and more especially to engines in which a gas or 15 vapor and air are mingled in suitable proportions and the mixture is then introduced into the cylinder or explosion-chamber. In such engines it has been proposed heretofore instead of shutting off altogether the supply of 20 explosive mixture when the engine is running too fast to reduce the supply of gas and of air proportionately, so that a smaller quantity of explosive mixture shall be formed and the force of the explosion reduced accordingly.

25 It is the object of my present invention to improve the means for regulating the supply of hydrocarbon and air, and especially with a view to permitting the proportions of hydrocarbon and air to be varied at will, even while 30 the engine is in operation, so that the character of the explosive mixture may be controlled and regulated according to the requirements or conditions under which the engine may be operating at the time.

35 The several features of my improvement will be more particularly pointed out hereinafter with reference to the accompanying drawings, in which I have represented a practical and convenient embodiment of my invention.

40 In the drawings, Figure 1 is a side elevation of an engine to which my improvements are applied, the driving or crank shaft being shown in section. Fig. 2 is a detail view on 45 a larger scale, showing the governing mechanism in end view and its connections to the valves. Fig. 3 is a side elevation of the governing mechanism. Fig. 4 is an elevation of the valve-boxes and a portion of the valve- 50 actuating mechanism as seen from the right in Figs. 1 and 2. Fig. 5 is an elevation of the same as seen from the right in Fig. 4, and

Fig. 6 is a sectional view showing the valves and the mixer.

The crank-shaft C in the engine shown in 55 the drawings is mounted in suitable bearings upon the bed-plate or pedestal A, while the cylinder E is supported by standards D above the crank-shaft, to which the piston (not shown) is connected by a piston-rod F, as 60 usual. The inlet and exhaust ports (represented at *h* and *h'*) may be controlled, as usual, by valves which may be operated by any suitable means, such as the links *i*², levers *i*³, and grooved gear I, which is engaged and driven 65 by a pinion on the crank-shaft. The hydrocarbon, in this particular instance in the form of vapor and air, is delivered to the inlet-port *h* through independent valve-boxes M and M', with a valve *m* in each to control the 70 corresponding port *m'*. These valves are operated together under the influence of the governing mechanism to vary the quantity of the explosive mixture according to the speed of the engine, and each is adjustable 75 independently of the other in order to permit the quality of the mixture to be varied as circumstances may require. Various arrangements might be devised for permitting the simultaneous operation and the independent 80 adjustability of the valves, but I prefer that shown in the drawings, in which each valve is a rotary oscillating valve mounted rigidly upon a shaft or stem *m*², which has bearings in the ends of the valve-box. Outside of the 85 valve-box each stem *m*² has fixed thereto a toothed sector *m*³. An arm *m*⁴ is mounted loosely upon each stem and carries a worm *m*⁵, which engages the corresponding sector, so that by rotation of the worm the position 90 of the sector *m*³, and consequently the position of the valve *m*, with respect to the arm *m*⁴ can be varied at will, thereby varying also the position of the valve with respect to the port *m'*, so that the valve shall open more or 95 less during its oscillation and shall vary the proportion of air or gas accordingly. The free ends of the two arms *m*⁴ are connected by a link *m*⁶ and are shifted simultaneously through suitable intermediate devices, presently to be described, by the action of the governor.

100 It will be obvious that so far as the action of the valves is concerned any form of gov-

ernor mechanism which is adapted for the purpose may be employed, but I prefer that shown in Figs. 2 and 3. As there represented, the entire governor mechanism is mounted 5 upon a sleeve N, which is secured to the crank-shaft C to rotate therewith. At one end of the sleeve N is a flange n, upon which are mounted the weighted bell - cranks n', the weighted arms of said bell-cranks being held 10 normally toward the axis of the shaft by springs n², which may be provided with adjusting devices n³. The other arms of the bell-cranks engage a second sleeve n⁴, which is movable longitudinally upon the sleeve N 15 and is grooved to be engaged by a forked or other lever n⁵, which is pivoted upon a suitable support. The outer end of the lever n⁵ is connected to one arm of a bell-crank n⁶, the other arm of which is connected by an adjustable rod n⁷ with the link m⁸, above referred to. It will be obvious that when the speed of the engine increases, so as to throw outward the weighted arms of the bell-cranks n', the sleeve n¹ will be shifted longitudinally and 25 through the described connections, or other equivalent connections which may be substituted therefor, will shift the valves m to reduce simultaneously the area of the ports through which the hydrocarbon and air escape into the mixing-chamber, so that the 30 quantity of the explosive mixture will be varied without varying the proportion of the hydrocarbon and air.

In order that the hydrocarbon and air may 35 be thoroughly mixed before they pass into the explosion-chamber or cylinder, I have provided a mixer, as at O, through which the hydrocarbon and air must pass from the valve-

port m' to the explosion-chamber. This consists merely of a shell within which are concentrically mounted upon suitable bearings two oppositely-disposed fan-wheels o and o'. These are so light that they are rotated by the passage of the gas and air through the shells, and as they rotate in opposite directions they insure the thorough mixing of the gas and air.

It will be obvious that various changes might be made in the form and arrangement of the parts herein referred to without departing from the spirit of my invention, and therefore it is to be understood that I do not intend to limit the invention to the precise construction and arrangement shown.

I claim as my invention—

In an explosive-engine, the combination of independent, rotary oscillating valves for admission of hydrocarbon and air separately, toothed sectors secured to the stems of said valves respectively, arms mounted loosely on 60 said stems respectively, worms carried by said arms to engage said sectors respectively, a link connecting said arms to move together, a governor and a connection therefrom to said link, whereby said valves are oscillated together by the governor and are separately adjustable about the axis of oscillation to vary the relative proportions of hydrocarbon and air, substantially as shown and described.

This specification signed and witnessed this 5th day of October, A. D. 1897.

JOHN A. SECOR.
